UNITED STATES PATENT OFFICE.

HUGH W. HARRIS, OF PITTSBURGH, PENNSYLVANIA, ASSIGNOR TO UNDERWOOD TYPEWRITER COMPANY, OF NEW YORK, N. Y., A CORPORATION OF DELAWARE.

TYPEWRITING MACHINE.

Application filed October 25, 1919. Serial No. 333,304.

To all whom it may concern:

Be it known that I, HUGH W. HARRIS, a citizen of the United States, residing in Pittsburgh, in the county of Allegheny and 5 State of Pennsylvania, have invented certain new and useful Improvements in Type-writing Machines, of which the following is a specification.

My invention relates to typewriting machines, and more particularly to paper-feeding and controlling devices therefor.

In conducting bookkeeping in which the items are typewritten on loose leaves by means of a typewriting machine, or a combined typewriting and computing machine, 15 it is desirable to print items simultaneously with the aid of carbon-paper, upon a bill or monthly statement of the customer's account, upon the customer's loose-leaf ledger-sheet, and upon a proof-sheet. The lines along which typewriting is to be effected may be and usually are at different heights upon the various sheets, and it is necessary, therefore, to assemble the sheets on the platen with the proper portion of each of the 20 sheets at the writing line of the machine. The adjustments necessary to properly assemble the sheets in the machine have been found to be troublesome and time-consuming, and it is a desideratum to obtain simple 25 and efficient means whereby the sheets may be fed to the platen and subsequently adjusted with reference to each other. Mechanism designed for this purpose is disclosed 30 in my Patent No. 1,294,456, dated February 18, 1919.

In the embodiment of my invention herein disclosed, the feed-rolls in engagement with the margins of the ledger-sheet are 40 mounted independently of the feed-rolls engaging the statement-sheet, the latter sheet being of less width than the ledger-sheet, which, in turn, is less in width than the proof-sheet.

In order to facilitate the adjustment of 45 the statement-sheet with reference to the ledger-sheet, and both the statement and ledger-sheets with reference to the proof-sheet, provision is made of means whereby 50 movement of a finger-piece to one position will effect withdrawal from effective position of the feed-rolls opposite the statement-sheet, and movement of the finger-piece to a second position will also effect withdrawal of the feed-rolls normally in en-

gagement with the margins of the ledger-sheet.

In order to detain or hold the statement-sheet when the feed-rolls normally co-operating therewith have been withdrawn and 60 the ledger and proof-sheets are advanced by the platen, provision is made of detaining devices arranged for engagement with the margins of the statement-sheet; such devices, as herein disclosed, comprising 65 friction members of rubber or other suitable material. Similar detaining devices are provided for co-operation with the margins of the ledger-sheet.

For the purpose of controlling the de- 70 taining devices, provision is made of means whereby, upon movement of a finger-piece to one position, the detaining devices associated with the statement-sheet will be made effective thereon, and, upon movement to a 75 second position, the detaining devices associated with the ledger-sheet will be rendered effective thereon.

The finger-piece controlling the detaining devices comprises a portion extending across 80 the front of the feed-roll controlling finger-piece. It follows from this arrangement that direct actuation of the finger-piece associated with the feed-rolls will cause them to be withdrawn from the platen, independ- 85 ently of any movement of the detaining devices, but that actuation of the detaining-device finger-piece will effect actuation of the other finger-piece.

Provision is also made of a detent device 90 associated with the feed-roll controlling finger-piece. This detent device is effective on the finger-piece in two different positions thereof, and, preferably, is insufficient in strength to maintain the finger-piece in po- 95 sition against the action of its restoring means, the principal purpose of the detent device being to indicate the positions to be assumed by the feed-roll controlling finger-piece to obtain certain results.

It will be understood that by actuation of 100 one finger-piece the statement-sheet feed-rolls may be released or all the feed-rolls may be released without affecting the detaining devices. Movement of the other 105 finger-piece to its intermediate position will, however, not only withdraw the feed-rolls from effective position with respect to the statement-sheet, but will render certain of the detaining devices effective on this sheet. 110

- If then the platen is rotated, the ledger and proof-sheets or record-sheets will be shifted with reference to the statement-sheet, the rough inner face of the outer carbon-sheet 5 causing it to travel with the ledger-sheet, since the outer smooth face of the carbon-sheet is adapted to slide readily upon the inner face of the statement-sheet. In the same manner, upon movement of the same 10 finger-piece to its second position, adjustment of the proof-sheet with reference to the other sheets may be effected. If desired, rollers to engage the margins of the proof-sheet may be provided.
- 15 Other features and advantages will hereinafter appear.

In the accompanying drawings,

- Figure 1 is a front view, showing my invention applied to a platen-frame of the 20 type used in the Remington typewriting machine.

Figure 2 is a rear view of the devices shown in Figure 1.

- Figure 3 is a sectional side elevation, 25 taken on the line 3—3 of Figure 2, showing the parts in normal position.

- Figure 4 is a view similar to Figure 3, but showing the parts in position to detain the statement-sheet while the ledger-sheet 30 and proof-sheet are being advanced.

- Figure 5 is a view similar to Figure 3, but showing the parts in position to detain the statement and ledger-sheets while the proof-sheet is being advanced.

- 35 Figure 6 is a fragmentary perspective view, showing the parts by which the detaining devices and feed-rolls are controlled.

- The platen 1, of the usual cylindrical 40 type, is carried by an axle 2, journaled in end-frames 3 and 4, which are connected by cross-bars 5 and 6. Finger-wheels 7 and 8 for actuating platen 1 are provided on the ends of axle 2, and suitable line-spacing 45 mechanism may be provided.

- Mounted in the end-frames 3 and 4, at the rear of the platen, is a shaft 9, carried by angular brackets 10 which are journaled at the ends of their upright-arms on a shaft 11, supported in said end-frames 3 and 4, and have forward extensions (not shown) secured to cross-bar 5. Mounted on shaft 9 are three-arm levers 12, six in number, the forward arms 13 of which are pivoted at 14 to carriers or yoke-pieces 15 at points intermediate of their ends. The yoke-pieces 15 extend transversely of the platen and beneath the same, and are provided at their ends with shafts 16 and 17, carrying forward 50 feed-rolls 18 and rear feed-rolls 19, respectively. In order to hold the feed-rollers 18 and 19 in effective position relative to the platen, helical springs 20 are connected to cross-bar 5 at one end, and, by 55 means of screws 20^a, to depending arms

21 of the three-arm levers 12. It will be seen that engagement of the screws 20^a in the coils of the helical springs 20 enables adjustment of the tension of the springs.

The shafts 16 and 17, opposite the central portion of the platen 1, are of greater length than the others, and each of them carries three rolls. Only one roll is supported on each of the other shafts.

In order to control the position of the 75 three-arm levers 12 and the effectiveness of the feed-rolls, shaft 11 is provided with a finger-piece or operating member 22 and with arms 23, secured at different angular positions on said shaft. Upon rotation of 80 shaft 11 by the finger-piece 22, the arms 23 will actuate the corresponding upwardly-extending arms 24 of the three-arm levers 12, and cause withdrawal of the carriers or yoke-pieces 15, and consequently of the 85 feed-rollers 18 and 19 from effective position with respect to the platen. The angular arrangement of arms 23 is such that the central feed-rollers will be withdrawn in advance of the end feed-rollers. Provision 90 is also made of detent means comprising a resilient arm 25, fixed on cross-bar 6, and provided with two downwardly-facing depressions to engage an offset portion 26 of finger-piece 22. Preferably, the strength 95 of the resilient arm 25 is insufficient to maintain finger-piece 22 in position against the urging of the returning means (shown in Figure 1 as a spring 26^a coiled about the shaft 11 adjacent the end-frame 100 3) and the detent device serves principally to indicate the positions to be assumed either for withdrawal of the central feed-rolls alone or for the withdrawal of all 105 of said feed-rolls.

It will be noted that the pivots at 14 are situated to the rear of the middle points of yoke-pieces 15. As a consequence of this arrangement the forward rolls 18 are withdrawn from the platen before the rear rolls 110 19, and, in order to insure withdrawal of said rear feed-rolls, resilient members 27 are secured on cross-bar 5 in position to co-operate with the forward feed-roller shafts 16. As seen in Figure 1, each of the 115 end members 27 serves to support one end of a shaft 16, while each of the intermediate members 27 supports the ends of two of said shafts and is forked to better adapt it for that purpose. Obviously, each of the 120 forked members 27 may be replaced by two single members.

A paper-table 28 is pivoted at 29 to forwardly-extending arms 30 of bell-crank pivoted on the shaft 9 and having depending arms 31 connected by springs 32 to the cross-bar 5. It will be seen that the springs 32 tend to maintain the paper-table in position to co-operate with the platen. At the rear, the paper-table rests floatingly against 125 130

certain of the parts supported on shaft 11. The depending arms 31 are provided with lugs 33 extending to the rear of the outside depending arms 21, so that withdrawal of the outer feed-rollers will effect withdrawal of the paper-table.

Upon movement of finger-piece 22 to its extreme rearward position, the feed-rollers and the paper-table will be moved away from the platen to permit the insertion of the work, which, in this case, comprises a statement-sheet A opposite the central rollers, a ledger-sheet B having its margins extending beyond the margins of the statement-sheet and in position to be engaged by the outer rollers, and a proof-sheet C extending laterally beyond the edges of the ledger-sheet, carbon-sheets being interleaved between the work-sheets. Upon release of the finger-piece 22, the feed-rollers and paper-table will be returned to their normal positions.

When the work-sheets are placed in co-operative position with the platen as just described, the lines along which typewriting is to be done may be at different heights upon the sheets. It will then be necessary to effect a relative adjustment of the sheets. To this end, provision is made of detaining devices whereby the statement-sheet may be held against movement while the ledger-sheet and proof-sheet are fed by the platen, or both the statement and ledger-sheets may be held while the proof-sheet is fed.

For the purpose of detaining or holding the statement-sheet A, provision is made of two friction members 34 of any suitable material, such as rubber, carried by resilient arms 35 secured to a bar 36. Said bar 36 is supported by levers, each of which comprises an arm 37 attached to one end of the bar, a collar 38 loosely mounted on shaft 11, and a rearwardly-extending arm 39. Provision is also made of ledger-sheet detaining means comprising levers 40 loosely mounted on shaft 11 and carrying friction members 41 at their forward ends. The friction members 34 are correctly laterally positioned for engaging the margins of the comparatively narrow statement-sheet A, while the friction members 41 are more widely separated for engaging the projecting margins of the wider ledger-sheet B.

Control of the detaining devices is effected by means of a shaft 42 carrying at its left end a finger-piece or operating member 43 bent to extend across the front of finger-piece 22. Secured to shaft 42 are cam arms 44 to engage arms 39 and cam arms 45 to engage levers 40, arms 44 and 45 being so positioned that arms 44 will cause movement of friction members 34 into engagement with the margins of the statement-sheet A, before arms 45 cause the movement of friction members 41 to effective position with reference

to the ledger-sheet B. As shown in Figure 5, cam arms 44 are provided with dwell portions 46, so that after movement of friction members 34 to operative position, arms 44 will be effective merely to prevent retraction 70 of friction members 34, while permitting continued rotation of the shaft 42, to operate the cam arms 45. Shaft 42 may be further rocked by finger-piece 43 to bring friction members 41 into contact with the ledger- 75 sheet B. It will be understood that resilient arms 35 serve to compensate for a slight overthrow of the cam arms 44 relatively to the cam arms 45, in order that both sets of friction members 34 and 41 may be brought 80 into effective position. Shaft 42 is carried by brackets 47 fixed on cross-bar 6, and the forward movement of finger-piece 43 is limited by stud 48 mounted in an arm 49 fixed on said cross-bar 6.

Operation of the device by means of finger-piece 43 is substantially as follows: Upon rearward movement of said finger-piece 43, finger-piece 22 will be moved to the rear, and when said finger-piece 22 reaches 90 the position to co-operate with the first depression in the resilient detent arm 25, the central feed-rollers will be withdrawn from contact with the statement-sheet A, and the friction members 34 will be moved into en- 95 gagement with said statement-sheet A. With the parts in this position, movement of the platen will cause feeding of the ledger and proof-sheets with reference to the statement-sheet. Further movement of finger-piece 43 to bring finger-piece 22 into position for its offset portion 26 to co-operate with the second depression in the resilient mem- 100 ber 25, will cause the withdrawal of the outer feed-rollers from engagement with the margins of the ledger-sheet B, and will ef- 105 fect movement of friction members 41 into engagement with said margins. With the parts in such positions, movement of the platen will effect feeding of the proof-sheet 110 with reference to both the ledger and state- 115 ment-sheets. The surface of the platen may be roughened to insure proper feeding of the proof-sheet C, and, if desired, provision may be made of the usual rollers supported in 115 position to engage the margins of the proof- sheet C.

Variations may be resorted to within the scope of the invention, and portions of the improvements may be used without others. 120

Having thus described my invention, I claim:

1. A paper-feeding device comprising, in combination, a revoluble platen to receive a plurality of superposed sheets diminishing 125 in width from the platen outward, feed-rolls arranged longitudinally of said platen, a pair of friction devices arranged to engage the margins of one of said sheets, and means to withdraw to ineffective positions the feed- 130

rolls opposite the same sheet, and to effect engagement of the margins thereof by the friction devices, thereby enabling the feeding by the platen of a sheet lying beneath 5 the sheet engaged by the friction devices while the latter sheet is held against movement.

2. In a typewriting machine, the combination with a revoluble platen around 10 which two superposed work-sheets and an interleaved carbon are fed, the margins of the inner sheet extending beyond the side edges of the outer sheet, of releasable feed-rolls to engage the outer sheet to press the 15 sheets against the platen, feed-rolls to engage the exposed margins of the inner sheet to press the same against the platen, and a normally ineffective friction device for lightly engaging the outer face of the outer 20 sheet and pressing the latter toward the platen, when the first-mentioned feed-rolls are released, thereby detaining the outer work-sheet to permit the inner work-sheet to be fed relatively thereto by the platen.

25 3. In a typewriting machine, the combination with a revoluble platen around which two superposed work-sheets and an interleaved carbon are fed, the margins of the inner sheet extending beyond the side edges 30 of the outer sheet, of releasable feed-rolls to engage the outer sheet to press the sheets against the platen, feed-rolls to engage the exposed margins of the inner sheet to press the same against the platen, a normally in- 35 effective friction device for lightly engaging the outer face of the outer sheet and pressing the latter toward the platen, when the first-mentioned feed-rolls are released, thereby detaining the outer work-sheet to 40 permit the inner work-sheet to be fed relatively thereto by the platen, a finger-piece, and means controlled by said finger-piece for concomitantly releasing the first mentioned feed-rolls and rendering said friction 45 device effective.

4. A paper-feeding device comprising, in combination, a revoluble platen to receive a plurality of sheets comprising a sheet of a certain width and a narrower sheet overlying 50 the same, a paper shelf for directing said sheets to said platen, central feed-rolls engaging the narrower sheet, outer feed-rolls engaging the margins of the first-mentioned sheet lying outside the margins of the 55 narrower sheet, means whereby said central feed-rolls may be withdrawn from the narrower sheet and the latter held against movement while the wider sheet is fed by the platen, means to withdraw the outer rolls 60 from effective position, and means actuated by said outer roll-withdrawing means for moving said paper shelf away from said platen.

5. In a typewriting machine, the combination with a revoluble platen around

which a plurality of superposed work-sheets and interleaved carbons are guided, said work-sheets diminishing in width progressively from the platen outwardly and comprising an outer sheet, an intermediate sheet 70 and an inner sheet, of releasable feed-rolls to engage the outer sheet to press the sheets against the platen, releasable feed-rolls to engage the margins of the intermediate sheet at each side of the outer sheet to press the 75 intermediate sheet against the platen, a detaining device for the outer sheet comprising friction members to engage the outer face of the latter adjacent its side edges, when the first-mentioned feed-rolls are released, to press the outer sheet lightly toward the platen and detain it while the intermediate sheet is fed by the platen, and a detaining device for the intermediate sheet comprising friction members movable to engage the outer face of the intermediate sheet near its side edges, when the first-mentioned and second-mentioned feed-rolls are released, to press the intermediate sheet 80 lightly towards the platen and detain it 85 while the inner sheet is fed by the platen.

6. In a typewriting machine, the combination with a revoluble platen for feeding a plurality of sheets, including an outer sheet and a wider sheet, thereunder, friction members spaced so as to be capable of engaging the margins of the outer sheet, friction members spaced for engagement with the margins of the wider sheet, and means for bringing the first-mentioned friction members 90 into engagement with said outer sheet to prevent feeding movement thereof by the platen, and for subsequently bringing said second-mentioned friction members into engagement with the wider sheet while maintaining the first-mentioned friction members 100 in effective position.

7. In a typewriting machine, the combination with a revoluble platen, of a pair of normally ineffective frictional detaining members for engaging the margins of a sheet on said platen to prevent feeding movement thereof by the platen, another pair of normally ineffective frictional detaining members for engaging the margins of a sheet 110 wider than the first and underlying the same to prevent feeding movement of this wider sheet by the platen, and operating means including an operating member for successively moving said pairs of frictional 115 detaining members into effective position one after the other, said operating means including yielding supports for the pair of said frictional detaining members first moved into effective position, to assure that both pairs of said frictional detaining members will be moved into effective position by 120 said operating means.

8. In a typewriter, the combination with a revoluble platen, of a series of feed-rolls 125

arranged longitudinally thereof, supporting devices for said feed-rolls including movable members and springs to maintain said members in position to render the respective 5 rolls effective with respect to said platen, a shaft, and arms fixed upon said shaft opposite said members and arranged at different angular positions, whereby actuation of said members may be effected in succession 10 by suitable rotation of said shaft.

9. In a typewriter, the combination with a revoluble platen, of a series of feed-rolls arranged longitudinally thereof, means to maintain the central rolls in effective position, including levers and springs urging said levers into position to render said rolls effective, similar means for holding the end feed-rolls in effective position, a shaft having arms arranged for simultaneous engagement 15 with the levers associated with the central rolls, and arms on said shaft positioned differently from said first-mentioned arms to actuate the end-rolls simultaneously and at a different time from said central 20 rolls.

10. The combination with a revoluble platen, of means associated therewith to enable simultaneous feeding thereby of a plurality of sheets progressively diminished 30 in width from the platen outward, and feeding of one of said sheets relatively to another, comprising a series of feed-rolls arranged longitudinally of the platen, groups of friction devices, those in each group being spaced in accordance with the width of one of said sheets, and means to release the feed-rolls corresponding to certain sheets, and to move the friction devices of the corresponding groups into engagement 35 with said sheets, thereby enabling one of said sheets to be held against movement, while another sheet is being fed by the platen.

11. In a typewriting machine, in combination, a revoluble platen, sheet-feeding means comprising a feed-roll for engaging an outer sheet on the platen, feed-rolls for engaging the projecting margins of a wider sheet underlying the outer sheet, a frictional 45 detaining device for engaging the outer sheet and lightly pressing it toward the platen to detain it while the wider sheet is shifted by the platen, a pair of frictional detaining devices to engage the margins of the wider sheet, while a work-sheet underlying the same is shifted by the platen, and feed-roll-release means to release from the control of the platen each work-sheet detained by said detaining devices.

12. A paper-feeding device comprising, in combination, a revoluble platen, a set of feed-rolls for maintaining a sheet in operative relation with said platen, a set of feed-rolls to engage the margins of a sheet of greater width and underlying the first-

mentioned sheet, a pair of friction members to engage the margins of the first-mentioned sheet, a pair of friction members to engage the margins of the second-mentioned sheet, means for withdrawing the first set of feed-rolls from the first-mentioned sheet, and subsequently the other set of rolls from the second-mentioned sheet, and means for placing the first-mentioned pair of friction members in engagement with the first- 70 mentioned sheet, and subsequently the second-mentioned pair of friction members in engagement with the second-mentioned sheet.

13. A paper-feeding device comprising, in combination, a revoluble platen, a set of feed-rolls for maintaining a sheet in operative relation with said platen, a set of feed-rolls to engage the margins of a sheet of greater width and underlying the first- 80 mentioned sheet, a pair of friction members to engage the margins of the first-mentioned sheet, a pair of friction members to engage the margins of the second-mentioned sheet, means for withdrawing the first set of feed-rolls from the first-mentioned sheet, and subsequently the other set of rolls from the second-mentioned sheet, means for placing the first-mentioned pair of friction members in engagement with the first-mentioned sheet, and subsequently the second-mentioned pair of friction members in engagement with the second-mentioned sheet, and means whereby actuation of the friction-member moving means will effect 90 engagement with the second-mentioned sheet, and means whereby actuation of the friction-member moving means will effect 95 engagement with the second-mentioned sheet, and means whereby actuation of the friction-member moving means will effect 100 engagement with the second-mentioned sheet.

14. The combination, with a platen, of a set of intermediate feed-rolls for engagement with a sheet on the platen, a set of outer feed-rolls for engagement with the 105 margins of a second sheet underlying the first and extending beyond the edges thereof, detaining means to prevent feeding of the first-mentioned sheet by the platen, detaining means for said second sheet, means 110 to withdraw said intermediate feed-rolls from effective position, means to withdraw said outer feed-rolls from effective position, means to render the detaining means for the first sheet effective thereon, and means 115 for rendering the detaining means for the second sheet effective thereon.

15. In a typewriting machine, the combination with a revoluble platen around which two superposed work-sheets and an interleaved carbon are guided, of releasable feed-rolls to engage the outside sheet to press the sheets against the platen, feed-rolls to engage the inner sheet to press the same against the platen, and a friction device 120 movable to engage the outer face of the outside sheet, when the first-mentioned feed-rolls are released, to press the latter sheet lightly toward the platen and detain it while the inner sheet is advanced by the platen. 125 130

16. The combination with a platen, of a set of intermediate feed-rolls for engagement with a sheet on the platen, a set of outer feed-rolls for engagement with the 5 margins of a second sheet underlying the first and extending beyond the edges thereof, detaining means to prevent feeding of the first-mentioned sheet by the platen, detaining means for said second sheet, means 10 to withdraw said intermediate feed-rolls from effective position, means to withdraw said outer feed-rolls from effective position, means to render the detaining means for the first sheet effective thereon, means for rendering the detaining means for the second sheet effective thereon, and means whereby actuation of the means to render effective the detaining means for one of said sheets will effect actuation of the withdrawing 15 means for the corresponding set of rolls.
17. The combination with a revoluble platen, of means including an intermediate feed-roll for engaging a sheet carried by said platen, outer feed-rolls for engagement 20 with the margins of a wider sheet underlying the first, a shaft, means whereby actuation of said shaft to one position will withdraw said intermediate roll from said platen, means whereby a further rotation 25 of said shaft will withdraw said outer rolls from effective position, and a detent device to determine the positions assumed by said shaft when said intermediate roll only has been withdrawn and when said outer rolls 30 have also been withdrawn.
18. The combination with a revoluble platen, of means including an intermediate feed-roll for engaging a sheet carried by said platen, outer feed-rolls for engagement 35 with the margins of a wider sheet underlying the first, a pair of detaining devices to engage the margins of the first sheet, a pair of detaining devices for engagement with said second sheet, means including a finger-piece 40 whereby said intermediate roll will be withdrawn when said finger-piece is in one position, and the outer rolls will be withdrawn when said finger-piece is in the second position, means including a second finger-piece 45 for successively rendering the pairs of detaining devices effective, and means whereby movement of the first-mentioned finger-piece to withdraw the feed-rolls may be effected independently of the second finger-piece, but movement of the second finger-piece to render the pairs of detaining devices effective will operate said first-mentioned finger-piece.
19. The combination with a revoluble 50 platen, of means for controlling the feeding by the platen of sheets associated therewith, comprising friction members arranged for engagement with the margins of a sheet on said platen, friction members arranged 55 for engagement with the margins of a sec- 60 ond sheet underlying the first, levers for controlling all of said friction members, and cam members for actuating said levers, the cam members for actuating the friction members associated with the first sheet being positioned in advance of the others, and provided with dwell portions to enable an additional movement thereof without further actuation of the corresponding levers. 70
20. In a typewriting machine, in combination, a revoluble platen to receive a plurality of superposed worksheets including a wider underlying sheet of which the margin projects laterally beyond a narrower top sheet, a normally ineffective friction-member movable into frictional engagement with the narrower top sheet to hold the same stationary while the wider underlying sheet is fed forward or backward by the platen, a similar normally ineffective friction-member movable into frictional engagement with the projecting margin of the wider underlying sheet for holding this sheet also stationary while another sheet underlying this said wider sheet is fed 80 forward or backward by the platen, and manually-operable means including a finger-piece for first moving the first-mentioned friction-member into effective position in engagement with said narrower top sheet and for subsequently by continued movement of said finger-piece moving said last-mentioned friction-member into effective position in engagement with the projecting margin of said underlying wider sheet while 90 maintaining the first-mentioned friction-member in its effective position in engagement with said narrower top sheet. 100
21. In a typewriting machine, in combination, a revoluble platen to receive a plurality of superposed work-sheets including a wider underlying sheet of which the margin projects laterally beyond a narrower top sheet, a normally ineffective friction-member movable into frictional engagement with the narrower top sheet to hold the same stationary while the wider underlying sheet is fed forward or backward by the platen, a similar normally ineffective friction-member movable into frictional engagement with the projecting margin of the wider underlying sheet for holding this sheet also stationary while another sheet underlying this said wider sheet is fed forward or backward by the platen, and manually operable means including a finger-piece 110 for first moving the first-mentioned friction-member into effective position in engagement with said narrower top sheet and for subsequently by continued movement of said finger-piece moving said last-mentioned friction-member into effective position in engagement with the projecting margin of said underlying wider sheet while maintaining the first-mentioned friction-member in its effective position in engagement with said narrower top sheet. 115
22. In a typewriting machine, in combination, a revoluble platen to receive a plurality of superposed work-sheets including a wider underlying sheet of which the margin projects laterally beyond a narrower top sheet, a normally ineffective friction-member movable into frictional engagement with the narrower top sheet to hold the same stationary while the wider underlying sheet is fed forward or backward by the platen, a similar normally ineffective friction-member movable into frictional engagement with the projecting margin of the wider underlying sheet for holding this sheet also stationary while another sheet underlying this said wider sheet is fed forward or backward by the platen, and manually operable means including a finger-piece for first moving the first-mentioned friction-member into effective position in engagement with said narrower top sheet and for subsequently by continued movement of said finger-piece moving said last-mentioned friction-member into effective position in engagement with the projecting margin of said underlying wider sheet while maintaining the first-mentioned friction-member in its effective position in engagement with said narrower top sheet. 125
23. In a typewriting machine, in combination, a revoluble platen to receive a plurality of superposed work-sheets including a wider underlying sheet of which the margin projects laterally beyond a narrower top sheet, a normally ineffective friction-member movable into frictional engagement with the narrower top sheet to hold the same stationary while the wider underlying sheet is fed forward or backward by the platen, a similar normally ineffective friction-member movable into frictional engagement with the projecting margin of the wider underlying sheet for holding this sheet also stationary while another sheet underlying this said wider sheet is fed forward or backward by the platen, and manually operable means including a finger-piece for first moving the first-mentioned friction-member into effective position in engagement with said narrower top sheet and for subsequently by continued movement of said finger-piece moving said last-mentioned friction-member into effective position in engagement with the projecting margin of said underlying wider sheet while maintaining the first-mentioned friction-member in its effective position in engagement with said narrower top sheet. 130

its effective position in engagement with said narrower top sheet, said manually operable means including a yielding support for said first-mentioned friction-member to assure 5 that both of said friction-members will be moved into effective position by said manually-operable means.

22. In a typewriting machine, the combination with a revoluble platen for feeding 10 a plurality of sheets, including an outer sheet and a wider sheet, thereunder, of friction-members spaced so as to be capable of engaging the margins of the outer sheet, friction-members spaced for engagement 15 with the margins of the wider sheet, and operating means for bringing the first-men-

tioned friction-members into engagement with said outer sheet to prevent feeding movement thereof by the platen, and for subsequently bringing said second-men- 20 tioned friction-members into engagement with the wider sheet while maintaining the first-mentioned friction-members in effective position, said operating means including yielding supports for said first-mentioned 25 friction-members to assure that all of said friction-members will be brought into effective position by said operating means.

HUGH W. HARRIS.
